UNITED STATES PATENT OFFICE.

JOHN B. KELLY, OF CHICAGO, ILLINOIS.

DEMOUNTABLE WHEEL.

1,144,136.

Specification of Letters Patent. Patented June 22, 1915.

Application filed January 21, 1915. Serial No. 3,443.

To all whom it may concern:

Be it known that I, JOHN B. KELLY, a citizen of the United States, residing at 5958 Washington Boulevard, Chicago, in the county of Cook and State of Illinois, have invented a new and useful Improvement in Demountable Wheels, of which the following is a specification.

My invention relates more particularly to demountable wheels of the type employing an inner hub member, an outer hub member adapted to be telescoped therewith and provided with means for preventing accidental separation of the hub members longitudinally of each other, and a key adapted to be assembled with said hub members and operating to prevent relative rotation of the latter when the wheel is in use; and my objects, generally stated, are to provide an improved construction of demountable wheel which shall be simple of construction, economical of manufacture, easily and quickly removed and replaced, firmly locked in position, and which shall not be subject to wear impairing its restraint against its lateral movement on its support.

Referring to the accompanying drawings Figure 1 is a view in longitudinal sectional elevation of the hub portion of a wheel constructed in accordance with my invention. Fig. 2 is a section taken at the line 2 on Fig. 1, and viewed in the direction of the arrow. Fig. 3 is a view in side elevation of the inner hub member of the wheel. Fig. 4 is a section taken at the line 4 on Fig. 3, and viewed in the direction of the arrow. Fig. 5 is a section taken at the line 5 on Fig. 1, and viewed in the direction of the arrow. Fig. 6 is a view in side elevation, partly broken, of the key employed for interlocking the hub members together against relative rotation; Fig. 7 is a section taken at the line 7 on Fig. 1, and viewed in the direction of the arrow. Fig. 8 is a section taken at the line 8 on Fig. 1, and viewed in the direction of the arrow; and Fig. 9, a top plan view of one of the members for holding the inner hub member against rotation when rotatably mounted on an axle other than a driving axle.

The hub portion of the wheel comprises three separable members 8, 9 and 10, which,

when assembled for use, are releasably interlocked with each other to produce a rigid structure, as hereinafter described. The 55 member 8, in practice, would not, by preference, be removable in the demounting operation, with the member 9 which carries the spokes, but would be connected with the driving axle, not shown, of the vehicle, in 60 any suitable manner as is well known in the art, when the wheel is a driving wheel, as for example, the rear wheel of an automobile, and when not a driving wheel, as in the case of the front wheel of an automobile, 65 would be journaled on a stationary axle, as for example, that shown at "X," or fixed on a rotary axle, not shown.

The member 8, in the construction illustrated, is of an internal form adapting it 70 to be journaled on the shaft "X," in accordance with well known practice. The member 8 is provided at its inner end with an annular beveled surface 11 which forms a frustum of a cone with its smaller end toward the outer end of the member 8, an annular shoulder 12 by preference being provided on the member 8 adjacent to the inner end of the surface 11. Beyond the beveled surface 11 and spaced therefrom, on 75 the member 8, are lugs 13 each extending through an arc preferably slightly less than 90° and equidistantly spaced from each other, it being preferred that other lugs 14 spaced similar to the lugs 13 and provided 80 between the tapered surface 11 and the lugs 13, be provided on the member 8 for co-operation with a key and a wedge-ring, hereinafter described.

The member 9 is in the form of a hollow 90 cylinder to which the spokes of the wheel would be attached, as for example, at the openings 15 toward its opposite ends. The member 9 near its inner end is provided internally with an annular beveled surface 16 95 preferably concentric with the surface 11 and of slightly larger diameter, between which surfaces a split-ring 17 is located for a purpose hereinafter described. Between the tapered surface 16 and the outer end of 100 the member 9, are lugs 18 spaced circumferentially of the member 9 preferably more than 90°, each of the lugs 18 being of a width circumferentially equal to the width

of the lugs 13, whereby the member 9 may telescope with the member 8 upon registering the lugs 18 with the circumferentially disposed spaces between the ends of the flanges 13. The member 10, which is in the form of a cylindrical sleeve cut away at diametrically opposed sides through arcs of preferably less than 90° , leaving curved sections 19 connected at one end by a rim section 10^a, forms a key for the members 8 and 9, and upon rotating the member 9 on the member 8, to a position in which the lugs 13 and 18 align lengthwise of these members, after the latter are telescoped together, as hereinbefore stated, may be inserted at its sections 19 into the longitudinally extending channels thus afforded between the ends of the lugs 13 and the ends of the lugs 18, to the position illustrated, in which it snugly fits, the interlocking of the key 10 with the lugs 13 and 18 preventing the member 9 from turning on the member 8, the parts thus formed and interfitting forming, in effect, a breach-lock.

In assembling the member 9, with the member 8, as hereinbefore explained, the split-ring 17, which is of springy material, such as steel, and is preferably normally of larger diameter than the diameter of the surface 11 with its ends normally spaced apart, becomes wedged between the surfaces 11 and 16, as represented in Fig. 1, the parts of the structure being so proportioned that when the ring 17 becomes wedged, as stated, the lugs 18 will extend in such position relative to the lugs 13 that when the member 9 is rotated to carry these lugs into alignment with each other longitudinally of the wheel hub, the outer ends of the lugs 18 will pass the inner ends of the lugs 13 but fit closely against the latter, this feature of the construction preventing any lateral play of the member 9 on the member 8, with the manifest advantage, this provision against lateral play, being maintained effective, by reason of the above described construction under continuous use of the wheel. The lugs 14 are provided for the purpose of forming a desirable bearing surface for the inner ends of the key-member 10 to prevent canting of said member when the wheel is in use, though they may be dispensed with, if desired.

Means are preferably provided on the member 10 for preventing the latter from accidentally working out of operative position under the conditions of use to which the wheel is put, these means, in the construction illustrated, comprising a tubular member 20 which is secured at its opposite ends in diametrically opposed openings 21 in the rim section 10^a of the member 10, this tube containing a plunger 22 adapted to be projected at one end through an open end

of the tube 20, through the medium of a coiled spring 23 confined in the tube 20 between the opposite, closed, end of the tube and a shouldered portion 24 of the plunger, the latter being provided with a cross-pin 25 extending through slots 26 in the tube 20 through the medium of which the operator may retract the plunger 22 into the tube 20. The outer end of the member 9 is provided about its inner periphery with a groove 27 affording a shoulder 28 which opposes the enlarged portion 10^a of the key 10 and into-interlocking engagement with which, the plunger 22 is normally projected by the spring 23 when the key 10 is in interlocking position, it being readily understood from the foregoing that this feature of the construction prevents the key from shifting outwardly on the member 8.

When it is desired, a cap member such as that represented at 29, may be provided for the outer end of the wheel hub. The cap member shown screws at the threaded portion 30 into the internally threaded portion 31 of the member 8 and fits, at an annular flanged portion 32 surrounding its threaded portion 30, against the outer end of the member 10, the outer surface of this flange being preferably beveled, as indicated at 33 and adapted to wedge against a similar beveled surface 34 on the interior of the member 9. It is preferred that means be provided at the inner end of the outer hub member 9 for steadyng the latter in use and preventing the spokes at this end of the wheel, especially where wire-spokes are used, from becoming displaced, these means in the illustrated construction comprising an annular flange 8 provided on the enlarged inner end of the member 8, with which the inner end of the hub member 9 telescopes and preferably snugly fits.

Where the wheel is not a driving wheel, in which case it is either journaled on an axle as in the construction illustrated, or fixed on a stub axle, some means should be provided for holding the inner hub member 8 against rotation during the operation of removing the wheel. This is effectively accomplished, in the construction illustrated, by means of a member 35 adapted to be applied to, and removed from, the adjacent spindle-post of the axle construction usually provided and represented at 36, the member 35 containing a curved socket 37 for this purpose, and containing in its opposite face an upwardly tapering channel 38 which is adapted to receive a lug 39 provided on the inner face of the inner end of the hub member 8, when the member 35 is positioned on the spindle-post 36, as hereinbefore stated, whereby the member 8 is locked against rotation and the outer hub member 9 may be readily manipulated to either as

semble or disassemble the removable parts of the hub-construction.

It will be readily understood from the foregoing that the wheel may be easily and 5 quickly removed from the member 8 and replaced thereon, and when secured in place, is positively locked against rotation independently of the member 8 and against lateral displacement thereof.

10. What I claim as new and desire to secure by Letters Patent is:—

1. A demountable hub formed of telescoping members provided with projections which interlock with each other upon rotating said members relative to each other and prevent said members from being separated longitudinally of each other, wedge surfaces on said members, a third member interposed between said wedge surfaces and 20 adapted to be in clamped position between said wedge surfaces when said projections are interlocked, and means engaging said projections for preventing said members from turning relative to each other.

25. 2. A demountable hub formed of telescoping members provided with projections which interlock with each other upon rotating said members relative to each other and prevent said members from being separated longitudinally of each other, wedge surfaces on said members, a ring adapted to be in clamped position between said wedge surfaces when said projections are interlocked, and means engaging said projections 30 for preventing said members from turning relative to each other.

35. 3. A demountable hub formed of telescoping members provided with projections which interlock with each other upon rotating said members relative to each other and prevent said members from being separated longitudinally of each other, wedge surfaces on said members, a split ring adapted to be in clamped position between 40 said wedge surfaces when said projections are interlocked, and means engaging said projections for preventing said members from turning relative to each other.

45. 4. A demountable hub formed of telescoping members provided with projections which interlock with each other upon rotating said members relative to each other and prevent said members from being separated longitudinally of each other, annular 50 beveled surfaces on said members, a ring adapted to extend in clamped position between said surfaces when said lugs are interlocked, and means engaging with said projections for preventing said members from turning relative to each other.

55. 5. A demountable hub formed of telescoping members provided with projections which interlock with each other upon rotating said members relative to each other

and prevent said members from being separated longitudinally of each other, annular beveled surfaces on said members, a split ring adapted to extend in clamped position between said surfaces when said lugs are interlocked, and means engaging with said 65 projections for preventing said members from turning relative to each other.

6. A demountable hub formed of telescoping members provided with projections which interlock with each other upon rotating said members relative to each other and prevent said members from being separated 75 longitudinally of each other, annular beveled surfaces on said members, a wedge-shaped ring adapted to extend in clamped position between said surfaces when said lugs are interlocked, and means engaging with said 80 projections for preventing said members from turning relative to each other.

7. A demountable hub formed of telescoping members provided with projections which interlock with each other upon rotating said members relative to each other and prevent said members from being separated 85 longitudinally of each other, annular beveled surfaces on said members disposed one within the other, a stop at the end of said innermost annular surface, a wedge-shaped ring surrounding said last referred to annular beveled surface, with the diameter of the 90 small end of the ring less than the diameter of the small end of said last referred to annular surface, and means engaging with said 95 projections, for preventing said members from turning relative to each other.

100. 8. A demountable hub formed of telescoping members provided with projections which interlock with each other upon rotating said members relative to each other and prevent said members from being separated longitudinally of each other, a third member disposed between said first-named members and engaging said projections for preventing said members from turning relative to each other, a retractable projection 105 carried by said third member, and a shoulder on one of said first-named members with which said projection engages when the latter is extended.

110. 9. In a vehicle, the combination of an axle, a hub mounted thereon and formed of relatively rotatable parts, means for releasably locking said hub members together to prevent relative movement, and means engaging a relatively stationary portion of the 115 vehicle and one of said hub members for holding the latter against rotation when the other of said hub members is rotated to disengage it from its cooperating hub member.

120. 10. In a vehicle, the combination of an axle, a hub formed of telescoping members mounted on said axle, one of said members being rotatable relative to the other thereof,

means for interlocking said hub members with each other involving the rotation of one of said members relative to the other thereof, and means engaging a stationary part 5 of the vehicle and the innermost one of said hub members for releasably holding it against rotation in the act of removing the

outer one of said hub sections from the inner hub section.

JOHN B. KELLY.
